UNITED STATES PATENT OFFICE.

ERNEST F. LLOYD, OF DETROIT, MICHIGAN.

CURB AND HOLDFAST FOR GAS-PURIFIERS.

1,080,705.

Specification of Letters Patent.

Patented Dec. 9, 1913.

Application filed December 6, 1912. Serial No. 735,201.

To all whom it may concern:

Be it known that I, ERNEST F. LLOYD, a citizen of the United States of America, residing at Detroit, in the county of Wayne and State of Michigan, have invented certain new and useful Improvements in Curbs and Holdfasts for Gas-Purifiers, of which the following is a specification, reference being had therein to the accompanying drawings.

This invention relates to clamping means for securing a closure on gas purifier tanks, holders, etc., and more especially to an arrangement thereof for holding the closure on the curb of a concrete tank, the parts being so disposed as to permit ready removal of the closure while they are also arranged so that unskilled labor may readily assemble the structure.

The invention relates to matters herein-after set forth and pointed out in the claims.

In the drawings, Figure 1 is a view in section of the curb of a division wall between two tanks provided with closures that are retained by clamping means that embody features of the invention; Fig. 2 is a similar view showing an outer wall of a tank with a slight modification of the clamping means; and Fig. 3 is a plan view in detail of a part of a clamping bolt taken on or about line III—III of Fig. 1.

As herein shown in preferred form, a curb 1 of a tank wall or of the division wall between two embedded tanks is formed of concrete or like cementitious material in which I-beams 2 or sills are embedded with their upper flanges flush with the top of the curb. Angle plates 3 are secured to the webs of these I-beams or sills at regular intervals and are apertured in their horizontal flanges 4 to allow the passage of anchor rods 5. The latter are secured against longitudinal displacement by drag plates 6 near their ends or otherwise by reinforcing bars 7 around which the ends 8 of the rods (Fig. 2) are hooked. The upper end portions of the anchor rods are formed into or provided with transversely slotted heads 9 that rest upon the flanges 4 and are of such dimensions that they can only be placed adjacent the upper flanges of the beams 2 with the head slots transverse to the latter.

Bolts 10 are appropriately pivoted in the members 9 so as to pass through openings in projecting clamping plates 11 that extend

beyond the margins of the tank closures. Suitable nuts 12 force the clamps downwardly toward the curb 2.

As herein shown the clamping plates 11 are bolted to longitudinal beams 13 and transverse beams 14 of a closure having a deck plate 15 of suitable material with a side member 16 as indicated in Fig. 1. Angle plates 17 are used to connect the edge 65 of the deck with the side member while an exterior angle 18 and a retaining strip 19 serve to hold a gasket 20 in position to rest on the channels 2 or curb.

If preferred, the plate 16 may be replaced by a channel bar as indicated at 21, in which instance a gasket 22 that rests on the curb or curb beams, is suitably secured by any preferred means, as indicated, to a beam 23 whose oppositely extending upper flanges 75 24 support the deck and the lower flange of the member 21.

By either construction anchorage is obtained that effectively holds the closure to the curb and is so arranged that any unforeseen movement in the cement or mass of the curb does not throw the anchor members out of line with the side of the closure. Furthermore the disposition of the parts is such that it is impossible to embed the anchor rods unless they are turned in proper position to allow the swinging away of the upper portions from the closure when unclamping the latter. As indicated in Fig. 1 the construction enables the use of a comparatively narrow curb on the division wall between two tanks as the parts lie within a comparatively narrow space.

Obviously, changes in the details of construction may be made without departing from the spirit of my invention and I do not care to limit myself to any particular form or arrangement of parts.

What I claim is:—

1. The combination with the curb of a tank or the like and a closure therefor having a yielding gasket between it and the curb, of sill members embedded in the curb, anchor rods in the curb passing through guide openings in projections of the sill members, anchor bolts pivoted to the rods and clamping plates on the closure engaged by the bolts.

2. The combination with the curb of a tank or holder of cementitious material, and a closure, of means for forcing the closure to seat consisting of sill beams embedded in

the curb, lateral extensions thereon, anchor rods in the curb passing through apertures in the extensions, bolts pivoted to the rods and clamping plates on the closure engaged by the bolts.

3. The combination with the curb of a tank or holder of cementitious material, a closure therefor, and a gasket sealing the joint between the closure and sill, of sill beams embedded in the curb, lateral exten-

sions thereon, anchor rods in the curb passing through apertures in the extensions, bolts pivoted to the rods and clamping plates on the closure engaged by the bolts.

In testimony whereof I affix my signature 15 in presence of two witnesses.

ERNEST F. LLOYD.
